UNITED STATES PATENT OFFICE.

WILLIAM C. HOWARD, OF BROOKLYN, NEW YORK.

BUTTON.

SPECIFICATION forming part of Letters Patent No. 268,021, dated November 28, 1882.

Application filed June 3, 1882. (No model.)

To all whom it may concern:

Be it known that I, WILLIAM C. HOWARD, a citizen of the United States, residing in the city of Brooklyn, county of Kings, and State of New York, have invented certain new and useful Improvements in Buttons, fully described and represented in the following specification and the accompanying drawings, forming a part of the same.

10 The present invention relates to that class of buttons which are adapted to be fastened to a garment by means of a metallic pin, as distinguished from those which are attached by thread passing through an eye, and is an improvement upon the button shown in United States Letters Patent No. 222,309, granted to J. H. Robertson December 2, 1879. The button shown in said patent has its convex back provided with an inwardly-projecting tube, 15 through which the fastening-pin is passed, and over the edge of which it is clinched, a notch in the side of the pin engaging with the edge of the tube and holding the button secure whenever subjected to such a strain as would tend to straighten or unclinch the pin. Buttons of this description were troublesome to make and comparatively expensive, because it was necessary to make the tube and back separately and then solder or otherwise 20 secure them together.

It is the object of the present invention to produce a button of this general character which will be less troublesome and costly to manufacture than those heretofore used.

25 To that end the invention consists broadly in a button the back of which is simply provided with a central opening (the inwardly-projecting tube being omitted) and having a plain disk, also provided with a central opening, seated in its interior, in combination with a fastening-pin arranged to pass through said two openings and clinch over the edge of the interior disk.

In said drawings, Figures 1, 2, and 3 are 30 central vertical sections of the cover or top, the interior disk, and the back of the button, respectively. Fig. 4 is a central vertical section of the button and fastening-pin, showing the parts assembled and the pin clinched; and 35 Fig. 5 is a view of a fastening-pin provided

with a notch in its side, which, when the pin is clinched, engages with the edge of the opening in the interior disk.

The back A of the button is made of metal or any other suitable stiff material, and is of 55 any ordinary shape or design. At its center it is provided with an opening, a, for the reception of the fastening-pin. Above or within this back is seated the disk B, also of metal or other stiff material, and provided with a central opening, b, through which the fastening-pin likewise passes. The back A and disk B are so shaped, either by striking up a bulge, C, in the back, as shown in Figs. 3 and 4, or in any other convenient way, that a space, e, 60 is left between them, so that the bearings of the two upon the pin are some distance apart, which makes the pin firm and rigid when inserted and clinched.

The top or cover D is made of metal, cloth, 70 or, in fact, of any of the materials or combinations of materials usually employed for the purpose, and is secured to the back A by a turned-down portion, d, as shown in Figs. 1 and 4, or in any other appropriate manner. 75

The button thus formed being placed upon one side of the fabric, the broad-headed fastening-pin E is passed through the fabric from the opposite side, and its point e is turned over or clinched upon the upper side of the disk B, 80 as shown in Fig. 4, such clinching being sufficient to hold the button to the fabric against any ordinary strain.

When the pin E is made of metal which is very easily bent it may be found best to provide it with a notch, f, as shown in Fig. 5, located in such position that when the point is clinched said notch will engage with the edge of the opening b, and thus aid in holding the pin in position against strain. 85

By doing away with the inwardly-projecting tube and using instead thereof the plain disk B, the construction of the button is greatly simplified and the cost of its production is materially lessened, all of the parts being of such 95 shape that they can be readily struck up from plain disks by the use of a die.

What I claim is—

1. The combination, with the button provided with the interior disk having the central aper- 100

ture, of the fastening-pin having a broad head and a point adapted to clinch or turn down over said disk, substantially as described.

2. The combination, with the button provided with the interior disk having the central aperture, of the fastening-pin having a broad head and a notch in its side at such a distance from its head as to engage with the edge of the aperture in said disk, substantially as described.

In testimony whereof I have hereunto set my hand in the presence of two subscribing witnesses.

WILLIAM C. HOWARD.
